J. L. SKUTTLE

AUTOMATIC WATER CONTROL VALVE

Filed Dec. 12, 1927

INVENTOR.
John L. Skuttle.

BY Milton E. Lowry
ATTORNEY

UNITED STATES PATENT OFFICE.

JOHN L. SKUTTLE, OF MASON CITY, IOWA.

AUTOMATIC WATER-CONTROL VALVE.

Application filed December 12, 1927. Serial No. 239,414.

This invention relates to certain new and useful improvements in an automatic water control valve and more particularly to the type of automatic valve disclosed in patent 5 granted to John L. Skuttle, 1,368,364, dated February 15, 1921.

The automatic water control valve disclosed in this application is intended for effecting a constant supply of water for humidifying 10 purposes to the water pan of a hot air furnace, and being an improvement over patents granted to John L. Skuttle, this invention relates more particularly to a renewable valve seat and a retaining plate therefor. 15 With the above and other objects in view that will become apparent as the nature of the invention is better understood, the same consists in the novel form, combination and arrangement of parts hereinafter more fully 20 described, shown in the accompanying drawing and claimed.

In the accompanying drawing, wherein like reference numerals indicate corresponding parts throughout the several views,

25 Figure 1 is a vertical longitudinal sectional view of a float control water box in communication with a pipe line that is float valve controlled and further showing an outlet pipe for communicating with a water pan of a hot 30 air furnace;

Figure 2 is an enlarged fragmentary side elevation, partly in section of the float valve mechanism;

35 Figure 3 is a cross-sectional view taken on line 3—3 of Figure 2; and

Figure 4 is a longitudinal sectional view taken on line 4—4 of Figure 3 showing the renewable valve seat in the valve casing head and the retaining plate for the renewable 40 valve seat.

The object of this invention being to provide a constant water supply for the water pan of a hot air furnace for automatic humidification, the gist of this invention relates 45 particularly to a control valve of the float type for the water supply. As shown in Figure 1, the float control box 1 has a pipe connection 2 with a water supply line while the pipe 3 leading from the box 1 is adapted to 50 communicate with the water pan in the hot air furnace for the maintenance of constant supply from the float control box 1.

The float valve mechanism associated with the float control box 1 comprises a valve casing head 4 with a central opening 5 therein that is surrounded by an externally threaded

extension 6. The valve casing head 4 is located on the inside of the float control box 1 while the externally threaded extension 6 projects therethrough and to be retained in position by the jamb nut 7. The union 8 connects the valve extension 6 with the water supply pipe 2.

The inner face 9 of the valve casing head 4 is provided with a central opening 10 of a diameter greater than the opening 5 which accommodates the mounting of the removable valve seat 11. The valve seat may be constructed of any desired material such as hard rubber or bakelite and has a central 70 opening 12 formed therein. The renewable valve seat 11 is of a diameter comparable with the diameter of the opening 10 in the valve casing head to be forcibly positioned therein and frictionally retained. A retaining plate for the removable valve seat 11 is also provided, the plate 13 being engaged with the outer projecting end of the valve seat 11 as shown in Figure 4 and retained in position by the screws 14 passing therethrough and entering the valve casing head 4. The retaining plate 13 is provided with an opening 15 alined with the opening 12 in the valve seat to permit free passage of the valve.

The valve mounting and float associated therewith comprises a post 16 having the threaded end thereof engaged with the valve casing head 4, the lower end of the retaining plate 13 being cut away to provide a clearance 80 for the post 16. As shown more clearly in Figures 3 and 4, the outer end of the post 16 is bifurcated as at 17 for the reception of the plate 18 that is pivotally supported thereby upon the pin 19. The lower edge of the plate 95 18 carries a laterally projecting finger 20 that engages the lower side of the post 16 to limit downward pivotal movement of the plate. A conical plunger valve 21 is bifurcated at one end for straddling the upper end of the plate 19 and is pivotally attached thereto by the pin 22. A rod 23 is rigidly connected to the plate 18 at one of its ends while the other end is threaded for the adjustable reception of the ball float 24. The valve 21 is freely movable through the opening 15 in the plate 13 for engagement with the valve seat 11.

From the above detailed description of the invention, it is believed that the construction and operation thereof will at once be apparent, it being observed that the flow of water to the float control box 1 is automatically con-

trolled by the float 24, depending movement of the float being limited by the finger 20 upon the plate 18 engaging the post 16 as shown by dotted lines in Figure 2 when the

5 valve 21 is spaced from the seat 11. The operative end of the valve always remains positioned within the opening 15 in the retaining and guide plate 13 to insure the correct movement of the valve in moving toward its

10 seat 11.

It is essential that the valve 21 have perfect contact with the valve seat to eliminate leakage by way of the valve into the float control box. In many instances, foreign matter will 15 collect on the valve seat and result in scarring thereof and destroy its efficiency. By providing the removable valve seat 11, the same can be renewed whenever desired and being constructed of wear resisting material, such 20 as hard rubber or the like, the life of the valve will be greatly increased.

While there is herein shown and described the preferred embodiment of the invention, it is nevertheless to be understood that minor 25 changes may be made therein without departing from the spirit and scope of the invention as claimed.

What I claim as new is:—

1. In automatic water control of the character described, a valve casing head having 30 a passage therethrough forming a valve opening, a removable valve seat set into the opening of the head at the exposed side thereof, a retaining plate for the removable valve seat

attached to the valve casing head, and a float 35 controlled plunger valve mounted on the head and cooperating with the removable valve seat.

2. In automatic water control of the character described, a valve casing head having 40 a passage formed with a valve opening on the exterior surface of said head, a post projecting from said head, a plate pivoted to said post for vertical movement in its own plane, a float rod secured to said plate, a float on said 45 rod, a valve plunger pivoted to said plate, a finger projecting from said plate adjacent said post to limit its downward movement about its pivot, a removable valve seat set into the valve opening, and a retaining plate 50 for the removable seat.

3. In automatic water control of the character described, a valve casing head having a passage formed with a valve opening on the exterior surface of said head, a post projecting from said head, a plate pivoted to said post for vertical movement in its own plane, a float rod secured to said plate, a float on said 55 rod, a valve plunger pivoted to said plate, a finger projecting from said plate adjacent said post to limit its downward movement about its pivot, a removable valve seat set into the valve opening, a retaining plate for the removable seat, and said retaining plate having an opening therein for the passage and 60 guidance of the plunger valve.

In testimony whereof I affix my signature.
JOHN L. SKUTTLE.
